UNITED STATES PATENT OFFICE.

CARL W. SWANSON, OF CHICAGO, ILLINOIS.

IRONING MACHINE.

Application filed July 19, 1916. Serial No. 110,081.

To all whom it may concern:

Be it known that I, CARL W. SWANSON, a citizen of the United States, residing at Chicago, in the county of Cook and State 5 of Illinois, have invented certain new and useful Improvements in Ironing Machines, of which the following is a specification.

This invention relates to ironing machines.

10 It is particularly applicable to machines adapted for general household use.

One of the objects of the invention is to provide an improved ironing machine.

Another object is to provide an ironing 15 machine of simple construction and operation so that it is particularly applicable for household use.

Another object is to provide an efficient ironing machine.

20 Another object is to provide an ironing machine which may be operated with a minimum of effort.

Other objects of my invention may best 25 be appreciated from a consideration of a description of the machine in view of the accompanying drawings, wherein:

Fig. 1 is a front elevation of the ironing machine;

Fig. 2 is an end elevation thereof with 30 parts broken away, as the machine is seen from the right of Fig. 1;

Fig. 3 is a vertical section on line 3—3 of Fig. 1;

Fig. 4 is a plan view with parts broken 35 away;

Fig. 5 is a perspective view of fragments of the operating connections for the shoe;

Fig. 6 is a vertical section on line 6—6 of Fig. 3;

40 Fig. 7 is a detail of a fragment of the shoe operating mechanism, and

Fig. 8 is a fragmentary section on line 8—8 of Fig. 3.

10 indicates in general a suitable frame, 45 illustrated as comprising lower side members 11 and 12, connected at top and bottom by tie-rods 13—13' and 14—14', the upper rods affording support for a table-plate 15,

that preferably is wide enough to protrude 50 at the front of the machine, and that preferably has its extremities rolled as at 15'

for smooth finish and for hook engagement, if desired, with either of the supporting rods 13—13'. Superimposed on the lower frames 11 and 12 are upper frame castings 55 16 and 17, suitably bolted to the lower frame members, and affording support to the feed cylinder and the cooperating shoe or pressing element. A feed table 20, supported on the upper frame members, directs the work 60 to the upper arc of the feed cylinder 21, that is peripherally padded and cloth-covered, as at 22, in any appropriate fashion for adequate frictional engagement with the work. This cylinder is rotatable with 65 the shaft 23, which is driven in any suitable fashion, preferably by a motor 24, mounted in the lower part of the frame and communicating motion to the shaft 23 through a belt and gear reduction-train 70 generally indicated at 26, the elements of which are suitably mounted on the outside of frame members 11—16 and are conveniently housed by a protective shell 27.

The shoe 30 that co-operates with the 75 feed cylinder may, of course, be of construction appropriate for the desired heating medium, whether electricity, gas, or otherwise, in this instance the shoe being shown as of the gas-heated type. The shoe affords 80 a smooth concaved surface 31 for co-operation with the periphery of the feed cylinder, and preferably spans somewhat less than half the surface of the cylinder, its receiving edge 32 being preferably sloped 85 away from the cylinder somewhat. As constructed for gas use the shoe is a hollow shell, having its outer wall 33 perforated, as at 34, for air circulation, and having within its interior a gas burner pipe 35 90 equipped with a suitable flexible connection 36 for communication with a source of gas supply.

The shoe 30, thus adapted to cover nearly 95 the rearward half of the cylinder, is carried by arms 37, journaled as at 38 to the contiguous frame members 16 and 17, preferably immediately below the shaft 23, so that the gravitational tendency of the shoe is to fall away from the cylinder. 100

I provide for control of the movements of the shoe by operating levers convenient

for foot operation to "close" the machine or bring the shoe and cylinder into working relation, and for either hand or foot operation to "open" the machine or move the 5 shoe away from the cylinder. And in operating the shoe I preferably use toggles to effect the shoe movements. Pivots connected to each end of the shoe is a compression link comprising an L-shaped member 10 40 to which is secured a rod 41 that extends slidingly into a yoke 42 and is surrounded by a spring 43 interposed between the parts 40, 42, so that the link structure may yield axially. This link constitutes one member 15 of a resilient toggle, its yoke 42 being pivotally connected as at 45 with a link 46 that is keyed on the shaft 47 (connecting the two toggles at opposite ends of the machine) journaled in frame members 16 and 20 17. To the hinge connection 45 of one of the two yielding toggles is connected a link 48 which is part of a second or operating toggle, said link being pivoted at 49 to one arm 50', of a bell crank lever 50, that is 25 mounted at 51 on frame member 11, the other arm 50'', of said lever being connected by link 52 to the foot lever 53 that is pivoted as at 54 to the frame member 11 at one end and that at its other end carries a 30 treadle 55. Raising of the free end of the lever 53 moves the bell crank arm 50'' upward, throws the arm 50' and connection 49 rearward and downward, breaking the joint of operating toggle 50', 48, which in 35 turn breaks the joint of yielding toggle 46, 39 so that the shoe 30 may tend to fall away from the feed cylinder 21 by gravity. To elevate the free end of lever 53 I pivot on the frame 11, a treadle lever 56 that has 40 its rear end 57 arranged to co-operate with the lever 53 to lift the latter. When treadle 55 is depressed both toggles are moved toward straight-line or locked position and the shoe 30 is returned toward closed or 45 pressing position, but when thick goods are fed to the machine the treadle-depression may stop before the toggles are thrown to straight-line position. The yielding toggle 39—46 ordinarily insures the proper press- 50 ing pressure between the cylinder and shoe for ordinary thicknesses of goods. Therefore when the toggles are locked in straight line or open position the operator ordinarily is relieved of the necessity of maintaining the pressure by pressing downwardly on treadle 55.

The normal or open position of the shoe relative to the cylinder may be controlled and its fall to such position may be cushioned. These results are accomplished by an adjustable retarding device 60, one end of which is connected to arm 50'' of lever 50 and the other end anchored to the machine frame. Retarding device 60 includes 65 a turnbuckle 61 and a spring 62. The

lower end of spring 62 is attached to a stud 63.

The stud may be fixed rigidly to the frame, but I prefer that it be mounted on a slide 64 that has play in a slotted guide 70 way 65 which, in turn, is suitably secured as by strap 66 to the tie rod 14' that connects the frame-members at a point above the levers 53, 56. By this latter provision, it will be apparent, the lever arm 50'' may 75 be elevated to a limited degree (determined by adjustment of the turn-buckle so loosely as to let pin 63 stand below the top of slot 63') without any resistance on the part of the spring 62, the plate 64 sliding in the 80 guide way 65; but after the stud 63 meets the end of slot 63' further elevation of the arm 50'' under the weight of the shoe is resisted by the spring, so as to cushion the gravity drop of the shoe, and to bring it to 85 rest in open position yieldingly and at a point that may accurately be predetermined by suitable adjustment of the turn-buckle 61. Further movement of the shoe to maximum distance from the cylinder may be 90 forced by application of pressure on the foot treadle 56 thereby to stretch the spring 62; and restoration of the shoe to closed or operating position may be effected by exerting downward pressure on the foot 95 treadle 55.

For hand control of the opening movement of the shoe with respect to the cylinder I provide a hand rail 70 at a point above the frame, preferably directly above the 100 cylinder, such rail connecting a pair of levers 71 that are pivoted as at 72 to the contiguous frame members 16 and 17, each such lever 71 having an arm 73 provided with a stud 74 that is arranged to work against 105 the joint 45 of the contiguous toggle 39—46. Thus when the hand rail 70 is thrown rearwardly both yielding toggles will be broken at their joints 45. The lever 71 at the appropriate end of the machine has 110 its arm 73 provided with a suitable extension finger 76 cooperating with a lever 77 that is mounted on the frame member 16 and that has an end-projection 78 crossing the joint 49 of the operating toggle 48—50, so that, 115 at the same time that lever arm 73 acts to break the toggle joint 45, the arm 76 moves the lever 77 to break the second toggle joint 49. This last said action, of course, requires slight raising of the foot lever 53, 120 but through the provision of the lost-motion anchorage for the spring 62, afforded by the slide plate 64 with its pin 63 working in its slot; this may be accomplished (when the parts are adjusted as shown in 125 Fig. 3) against only gravitational resistance, as the spring 62 does not come into play until the lever 50 has been moved a material distance. The hand-lever 70—71 may be moved in one direction only, as the 130

arm 76 is bent to provide a stop 76' coacting with an abutment 16' which may be a flange of the casting 16, so that lever 73 acts as a lock to prevent toggle joint 45 from breaking outward, and thus insures that when the intent is to close the machine, the yielding toggle may not be overthrown.

This facility for separating the shoe from the cylinder by hand manipulation when the 10 operator is standing at any point with respect to the machine is of importance especially in preventing the burning of the coverings of the padded cylinder. As a matter of convenience I provide at the side of 15 the machine, opposite the gearing, a hanger rod 80 slideable in a suitable bracket 81 carried by the frame end 12, and it will be apparent that an operator standing at the left end of the machine, Fig. 1, to hang previously pressed articles on this rod, may instantly open the machine when an article being pressed completes its passage through the roll and falls on table 15.

In the operation of the machine it will be 25 apparent that the padded cylinder feeds the work beneath the shoe which is stationary except for its yielding movements against the spring 41, and that the construction described affords a very capacious movement 30 of the shoe away from the cylinder to permit of work insertion. When the shoe is dropped away from the cylinder its forward edge constitutes an excellent gaging means by which the work, such as a sheet 35 or the like, may be started over the roller straight and true. A piece of work, whether thick or thin, properly placed on the roller and coming under the lip 32 of the shoe, will inevitably be fed straight through the 40 machine, the yielding links 39 of the yielding toggles compressing sufficiently to accommodate variations in thickness of the work. It will be observed that when the machine is in operation the shoe, as positioned by the spring element of the toggle, 45 is held against any possibility of accidental opening if the toggle 39-46 is straight or locked and is itself held in locked position by the toggle 48-50, which also may stand 50 straight or locked, the joint of each said toggle being capable only of movement in one direction because of contact of the two hinge joints 45 and 49 with the levers 73 and 77 which in turn are limited against 55 overthrow-movement by the locking of bend 76' against the flange of frame 16'.

In practice I have found the construction to be inexpensive, rugged, efficient, and capable of rapid and easy operation with 60 minimum labor on the part of the user.

While I have herein described with considerable particularity one embodiment of my invention for purposes of full disclosure it will be understood that many changes in 65 details of structure and arrangements may

be made within the scope of the appended claims.

Having described my invention, what I claim is:

1. An ironing machine comprising a feed 70 cylinder; a shoe pivotally connected to the frame for cooperation with the cylinder; a yielding toggle for normally holding the shoe in closed position; a second toggle controlling the yielding toggle; a foot lever to 75 close both toggles and means including another lever to directly break both toggles to permit the shoe to move away from operative position.

2. An ironing machine comprising a feed 80 cylinder; a shoe pivotally connected to the frame for cooperation with the cylinder; a yielding toggle for normally holding the shoe in closed position; a second toggle, one member of which is connected to the joint 85 of the first toggle and the other member prolonged into a composite crank arm; a lever connected to the crank arm to control both toggles and means including another lever having parts to engage the joints of both 90 toggles to directly break said toggles.

3. An ironing machine comprising two side frame members spaced apart and tied together; a rotatable feed cylinder journaled at its ends in bearings provided by the respective frame members; means carried by one said frame member to rotate said cylinder; a shoe for co-operation with the rotatable cylinder, pivoted at its ends in said respective frame members and below the 95 axis of said cylinder for movement to open position, two yielding toggles, supported, one on each frame member, for moving the shoe; a hand lever having a part extending substantially parallel with and above the cylinder and pivoted near each end thereof to open the toggles, and a foot lever arranged to close both toggles whereby the shoe is moved in parallel lines with respect to the cylinder.

4. An ironing machine having a frame; a rotatable feeding cylinder supported by the frame, a pressing shoe pivotally connected to the frame and for cooperation with the cylinder to press articles therebetween, a 105 resilient toggle for holding the shoe in pressing relation to the cylinder, an operating toggle for controlling the resilient toggle, means for extending the operating toggle to force the shoe toward the cylinder, a manual release for causing the closing of the toggles to separate shoe and cylinder, and means for cushioning the shoe in its separation from the cylinder.

5. An ironing machine having a frame, a 125 rotatable feeding cylinder supported by the frame, a pressing shoe pivotally connected to the frame and movable toward and from the cylinder, a resilient toggle for holding the shoe in pressing relation to the cylinder, 130

an operating toggle for controlling the resilient toggle, means for controlling the operating toggle to move the shoe to pressing position, and a manual release for controlling the toggles to separate the shoe and cylinder.

6. An ironing machine comprising two side frame members spaced apart and tied together; a rotatable feed cylinder journaled 10 at its ends in bearings provided by the respective frame members; means carried by one said frame member to rotate said cylinder; a shoe for co-operation with the rotatable cylinder for engagement with the 15 surface thereof pivoted at its ends in said respective frame members below the axis of the cylinder for gravity movement to open position; two yielding toggles comprising a pair of pivotally connected links for normally holding the shoe in closed position, the opposite ends of each toggle being connected respectively to a frame member and to the shoe, and the links connected to the shoe being resiliently extensible, said last mentioned 20 links lying substantially vertical when the toggle is open to cushion the opening movement of the shoe at each end; a lever, and connections between the lever and joints of the toggles for breaking said joints to permit movement of the shoe to open position.

7. An ironing machine having a frame, a feeding cylinder journaled thereto, a pressing shoe pivotally carried by the frame and movable to pressing and non-pressing relation to the cylinder, a resilient toggle for moving the shoe to pressing position, a manually actuated operating toggle for causing the resilient toggle to move the shoe to pressing position, a hand operated release for 35 causing the toggles to allow the shoe to move from pressing position, and means controlling such movement of the shoe from pressing position.

8. An ironing machine having a frame, a feeding cylinder journaled thereto, means for rotating the cylinder, a pressing shoe pivotally carried by the frame and movable to pressing and non-pressing relation to the cylinder, the shoe being movable to non- 45 pressing position by gravity, a resilient toggle for moving the shoe to pressing position and yieldingly holding the same in such position, a manually controlled operating toggle for controlling the resilient toggle, a release for the toggles to cause the same to 50 release the shoe from pressing position, and means for cushioning the movement of the shoe from pressing position.

9. An ironing machine comprising two side frame members spaced apart and tied together; a rotatable feed cylinder journaled 60 at its ends in bearings provided by the respective members; means carried by one of said frame members to rotate said cylinder; a shoe for co-operation with the rotatable

cylinder for engagement therewith pivoted at its ends in the said respective frame members and below the axis of said cylinder for gravity movement to open position; a pair of toggles supported on each frame member, 70 one of each pair connected to the frame member and to the shoe, the other toggle of each pair connected to the frame member and to the meeting ends of the links comprising the first mentioned toggle; the first mentioned 75 toggles each having a resilient, yielding member and means including a lever to close the second mentioned pair of toggles which in turn close the first mentioned pair of toggles, and means including another lever to 80 break both toggles.

10. An ironing machine comprising two side frame members spaced apart and tied together; a rotatable feed cylinder journaled 85 at its ends in bearings provided by the respective members; means carried by one said frame member to rotate said cylinder; a shoe for co-operation with the rotatable cylinder for engagement with the surfaces thereof, pivoted at its ends in said respective frame member, in a vertical plane immediately below the axis of said cylinder for gravity movement to open position; a pair of toggles pivoted to each frame member and to the shoe at its respective ends; said toggles each 90 having a yielding compressible member; another pair of toggles, each supported on a frame member, each said toggle having one of its ends pivoted to the frame member and the other to the members of the first mentioned toggle; a foot-operated lever for forcibly closing said toggles to raise the shoe into contact with said cylinder and means including a hand-operated lever extending 95 parallel with the cylinder and between the 100 two frames for opening both said toggles.

11. An ironing machine having a frame, a feeding cylinder journaled thereto, means for rotating the cylinder, a pressing shoe pivotally carried by the frame and movable to pressing 110 and non-pressing position relative to the cylinder, a resilient toggle for moving the shoe to pressing position and yieldingly holding the same in such position, an operating toggle acting to move the resilient toggle to pressing position, a foot lever for actuating the operating toggle to pressing position wherein the same is self retaining, and a hand controlled release extending along substantially the length of the machine and cooperating with the operating 115 toggle to close the same and release the shoe from pressing position.

12. An ironing machine having a frame, a pressing shoe pivoted thereto and movable 125 to pressing and non-pressing positions, a pair of cooperating toggles for moving the shoe to pressing position, manually controlled means for actuating one of the toggles to cause both toggles to open to move 130

the shoe to pressing position, a release acting against one of the toggles and causing the toggles to close and the shoe to move to non-
pressing position, and a rotatable cylinder
5 journaled to the frame and cooperating with the shoe in pressing position to pass and press articles therebetween.

In testimony whereof I hereunto set my hand in the presence of two subscribing witnesses.

CARL W. SWANSON.
